Primary Examiner — Susan Bennett Hattan*Assistant Examiner* — Lauren D McVey(74) *Attorney, Agent, or Firm* — Scully, Scott, Murphy & Presser, P.C.(57) **CLAIM**

The ornamental design for a networking device, as shown and described.

DESCRIPTION

FIG. 1 is a rear perspective view of a networking device showing my new design;

FIG. 2 is a front perspective view thereof;

FIG. 3 is a front elevation view thereof;

FIG. 4 is a rear elevation view thereof;

FIG. 5 is a top plan view thereof;

FIG. 6 is a side elevation view thereof; and,

FIG. 7 is an opposite side elevation view thereof.

The wire frame lines shown throughout the views are intended to indicate surface contour.

The broken lines are included for the purpose of illustrating portions of the article that form no part of the claimed design.

The bottom side of the article forms no part of the claimed design.
